Primary Examiner — Brian N. Vinson(74) *Attorney, Agent, or Firm* — Hamre, Schumann, Mueller & Larson, P.C.(57) **CLAIM**

The ornamental design for a light globe head and support, as shown and described.

DESCRIPTION

FIG. 1 is a perspective view of a light globe head and support showing our new design.

FIG. 2 is a left side planar view of FIG. 1 thereof.

FIG. 3 is a right side planar view of FIG. 1 thereof.

FIG. 4 is a back planar view of FIG. 1 thereof.

FIG. 5 is a front planar view of FIG. 1 thereof.

FIG. 6 is a top planar view of FIG. 1 thereof; and,

FIG. 7 is a bottom planar view of FIG. 1 thereof.

The broken line disclosure represents portions of the head and support which form no part of the claimed design.

1 Claim, 4 Drawing Sheets(56)
